[57] CLAIM

The ornamental design for test instrument for electric body stimulator, substantially as shown.

DESCRIPTION

FIG. 1 is a front elevational view of a test instrument for electrical body stimulator showing our new design;

FIG. 2 is a top plan view thereof;

FIG. 3 is a left side elevational view;

FIG. 4 is a right side elevational view;

FIG. 5 is a rear elevational view; and

FIG. 6 is a bottom plan view.

FIG. 2

FIG. 3

FIG. 1

FIG. 4

FIG. 5

FIG. 6
